DESIGN FOR A DRESS

Maurice Extract, New York, N. Y.

Application July 11, 1936, Serial No. 63,773

Term of patent 3½ years

To all whom it may concern:

Be it known that I, Maurice Extract, a citizen of the United States of America, residing in Manhattan, county of New York and State of New York, have invented a new, original, and ornamental Design for a Dress, of which the following is a specification, reference being had to the accompanying drawing, forming part thereof, wherein,

The design is characterized by an alternate arrangement of braid and tucks upon the tunic member of the dress, as shown.

I claim:

The ornamental design for a dress, substantially as shown and described.

MAURICE EXTRACT.
